UNITED STATES PATENT OFFICE.

FRANK MESZAROS, OF NEW YORK, N. Y.

TOOTHPICK-VENDING MACHINE.

1,191,715.

Specification of Letters Patent. Patented July 18, 1916.

Application filed June 10, 1915. Serial No. 33,315.

To all whom it may concern:

Be it known that I, FRANK MESZAROS, a citizen of the United States, and a resident of the city of New York, borough of Manhattan, in the county and State of New York, have invented a new and Improved Toothpick-Vending Machine, of which the following is a full, clear, and exact description.

10 This invention relates to vending machines and particularly to toothpick vending machines, and has for an object to provide an improved construction which will vend one toothpick at a time.

15 Another object in view is to provide an improved construction for vending toothpicks which will vend a certain quantity of toothpicks on each operation.

A still further object of the invention is to 20 provide a toothpick vending machine which is formed with an arrangement whereby the toothpicks are agitated on each operation and directed in a single line to the discharge point so that only a predetermined number 25 may be vended on each successive operation.

In the accompanying drawings:—Figure 1 is a perspective view of a device embodying the invention; Fig. 2 is a longitudinal vertical section through the construction 30 shown in Fig. 1; Fig. 3 is a sectional view through Fig. 2 on line 3—3; Fig. 4 is a detail vertical sectional view through Fig. 2 on line 4—4; Fig. 5 is a horizontal sectional view through Fig. 2 on line 5—5; Fig. 6 is 35 a longitudinal vertical section through the upper part of a machine embodying the invention, the parts being in a different position to that shown in Fig. 2.

Referring to the accompanying drawings 40 by numerals, 1 indicates a base of any desired kind and 2 a standard which may be formed from a tubular member and a clamping screw, as shown in Fig. 2, if desired, so as to rigidly hold the bracket 3 in position.

45 Rigidly secured to the bracket 3 is a case 4 which may be held in place by any suitable means, as for instance screw 5. The bracket 3 is provided with an aperture 6 and with a vertical extension 7 which receives the 50 journal pin 8 extending through lever 9. Lever 9 is provided with a thumb member 10 and with an arm 11, which arm is provided with a slot 12 for accommodating the pin 13 mounted in the bifurcated member

14 of rod 15. When lever 9 is depressed, as 55 shown in Fig. 6, the same operates freely in slot 6 and causes the rod 15 to move in one direction. A spring 17 causes the lever and associated parts to move in the opposite direction, said spring having one end bearing 60 against the bearing of case 4 and the opposite end against a feeding bar 18, which bar is provided with a plurality of fingers 19, each of which is formed with a beveled face 20. The fingers 19 are spaced a pre-determined distance from the side of the case 4, as for instance, a sufficient distance to allow the passage of one toothpick, though this distance could be increased, if desired, so as to allow two or more to pass. 70

The case 4 is provided with a front plate 21 of an appreciable thickness, which plate acts as a support for the lowermost toothpick in case 4, as clearly shown in Fig. 2. A slot 22 is provided in the plate 21 so as to 75 allow the pin 23 to move up and down, said pin being mounted in the bar 18 and carrying a sliding door 24. When lever 9 is moved downwardly, as shown in Fig. 6, the bar 18, together with door 24, is moved 80 downwardly, whereby a doorway is provided through which the toothpicks may pass to the supports 25. As the bar 18 moves downwardly the rod 15 is moved longitudinally and consequently moves the 85 transverse discharge bar 26 toward the door 24, said movement being sufficient to cause the fingers 27 of bar 26 to force the lowermost toothpick in the case outwardly through the opening or doorway 28 and at 90 the same time raise the remaining toothpicks so that none of the same can pass out of the case. The fingers 27 are each formed with a beveled portion 29 for raising the toothpicks remaining in the case, and with a flat portion 30 for forcing the lowermost toothpick out of the casing on to the supports 25. The fingers 19 of bar 18 and the side of the casing present a guideway 31 for a single row 95 of toothpicks, while in the casing an inclined filling block 32 is provided for directing the toothpicks in the casing to the guideway 31.

It will be noted that in Fig. 2 the device is closed and the fingers 19 are extending upwardly into the toothpicks. When the 105 device is operated a single toothpick is moved to the supports 25, as shown in Fig. 6, and the fingers 19 are lowered so that

the beveled surface 20 is in alinement with the bevel of the filling block 32. Upon releasing the lever 9 from the position shown in Fig. 6 the same will automatically move the parts to the position shown in Fig. 2 and will thus agitate the toothpicks so that there will always be supplied a row of toothpicks in the guideway 31 ready to be forced out one at a time on to the supports 25.

10 It is evident that any desired number of toothpicks may be secured from the device by successively working the same, but in any case the toothpicks are placed in the device so that each person operating the same may 15 secure a clean toothpick. This is very desirable in public eating houses, as each patron is assured of a clean toothpick and the proprietor is reasonably assured that none of the toothpicks will be wasted.

20 When it is desired to refill the case 4 the lid 33 is removed and a new supply is provided, said lid being telescopically fitted on the case so that it may be removed at any time. Lid 33 preferably carries cup-shaped 25 members 34 and 35 for receiving various articles as desired, as for instance, condiment holders. These members, of course, may be changed without departing from the spirit of the invention, and in fact, various 30 parts of the device may be changed somewhat if desired. The bar may be supported in any desired manner, as for instance by suitable guiding members 36 which are connected with the casing 4 in any suitable 35 manner.

What I claim is:—

1. In a toothpick vending machine of the character described, a casing provided with a doorway, a door for normally closing said doorway, a reciprocating member for moving said door to an open position, said reciprocating member acting also as a toothpick guide, means for forcing a toothpick through said doorway when the door is in 45 open position, and a manually operated member for actuating said moving parts in timed relation to each other.

2. A vending device for toothpicks, comprising a casing formed with a guideway 50 and with a doorway arranged adjacent the bottom of said guideway, a door for normally closing said doorway, a pivotally mounted lever for actuating said door, a sliding ejecting member, and means for connecting said sliding ejecting member with said lever, whereby said ejecting member is moved simultaneously with the movement of said door for forcing a toothpick from said guideway through said doorway immediately after the door is moved to an open 60 position.

3. In a vending machine for toothpicks, a casing for receiving a quantity of loose toothpicks, a reciprocating member arranged 65 on said casing and projecting into the space

occupied by the said toothpicks, said reciprocating member being arranged adjacent one side of the casing so as to provide a guideway for the toothpicks, a transversely movable ejector, a door, means for simultaneously opening said door for lowering said reciprocating member and moving said ejector so as to force the lowermost toothpick in said guideway from the casing, and means for restoring all of said members to their original position, whereby said reciprocating member will agitate the toothpicks in the casing so as to cause some of the same to aline themselves in said guideway ready for a second operation.

4. A toothpick vending machine, comprising a casing, a vertically movable stirring member arranged adjacent one of the walls of the casing and with said wall providing a guideway for the toothpicks, a pivotally mounted lever connected with said stirring member for moving the same in one direction, a spring for moving said stirring member in the opposite direction, and means connected with said lever for ejecting one 85 of the toothpicks in said guideway upon each movement of said lever.

5. A toothpick vending machine, comprising a casing, a bottom member arranged therein inclined so as to direct toothpicks 95 in the casing to one side of the casing, a stirring member arranged adjacent the side of the casing to which the toothpicks are directed by said bottom member, said stirring member and said casing forming a 100 guideway for receiving a single line of toothpicks, said casing being formed with an opening adjacent the bottom of said guideway, a door normally closing said opening, an ejector arranged opposite said 105 opening, and a lever connected with said door and said ejector for simultaneously opening said door and moving said ejector for ejecting the lowermost toothpick in said guideway from said opening.

6. A toothpick vending machine, comprising a casing for receiving toothpicks, a stirring member arranged in said casing adapted to stir and to aline the toothpicks, an ejecting member arranged opposite the 115 lowermost alined toothpicks, a lever for actuating said ejector, and means for operating said stirring member simultaneously with the operation of said ejector.

7. A toothpick vending machine, comprising a casing, a stirring member for the toothpicks in the casing, said stirring member being formed with a plurality of spaced fingers arranged adjacent one side of the casing so as to present a restricted portion defining a passageway for the toothpicks, whereby the toothpicks are alined, an ejecting member formed with a plurality of spaced fingers arranged to extend between the fingers of said stirring member, means 125 130

for operating said ejecting member for ejecting one of the toothpicks in said passage-way and lowering said stirring member simultaneously therewith, and a spring for returning said stirring member and said ejecting member.

5 In testimony whereof I have signed my

name to this specification in the presence of two subscribing witnesses.
